Primary Examiner — Cary M Robinson(57) **CLAIM**

The ornamental designs for a vehicle rear taillamp, as shown and described.

DESCRIPTION

FIG. 1 is a perspective view of an embodiment of the vehicle rear taillamp;

FIG. 2 is a front view of the embodiment of FIG. 1;

FIG. 3 is a side view of the embodiment of FIG. 1; and,

FIG. 4 is a top view of the embodiment of FIG. 1.

The broken lines in the drawings illustrate portions of the vehicle rear taillamps taillamp that form no part of the claimed design.
